COMBINED SAFETY RAZOR AND
SHARPENER

Edward Holbrook Wyman, Aiken, S. C.

Application October 7, 1933, Serial No. 692,647

2 Claims. (Cl. 30—12)

My invention relates to safety razors.

An important object of the invention is to provide a safety razor equipped with blade-sharpening means which does not interfere with the use of the razor in shaving.

5 A further object of the invention is to provide blade-sharpening means carried by one element of a safety razor, in such a manner that the sharpening means has a diagonal stroke during the sharpening operation.

10 A further object of the invention is to provide a safety razor of the above-mentioned character, equipped with sharpening means constituting a permanent part of the same without materially increasing the size, weight, or cost of the article.

15 A further object of the invention is to provide a safety razor of the above-mentioned character, which may be operated quickly and conveniently for sharpening the blade.

20 Other objects and advantages of the invention will be apparent during the course of the following description.

In the accompanying drawing, forming a part 25 of this specification, and in which like numerals are employed to designate like parts throughout the same,

Figure 1 is a perspective view of a safety razor embodying my invention,

30 Figure 2 is a central vertical longitudinal section through the same,

Figure 3 is a plan view of the same,

Figure 4 is a perspective view of the guard, and

35 Figure 5 is a perspective view of the blade-holding unit.

In the drawing, wherein for the purpose of illustration is shown a preferred embodiment of my invention, the numeral 10 designates a cap, provided centrally thereof with a rearwardly projecting screw-threaded stud 11, for screw-threaded engagement within a screw-threaded socket 12, carried by a rod or stem 13. The cap is provided upon its rear inner side with lugs 14, for insertion within openings formed in a double edge blade 15, as shown. A clamp 16 has an opening for the passage of the screw-threaded stud, and has openings or slots 17, for receiving the lugs. When the socket 12 is screwed upon the stud, it engages the clamp 16, and the flexible blade 15 is clamped to the cap 10. The cap, clamp, rod and socket constitute a blade-holding unit.

40 The numeral 18 designates a guard, provided 55 at its longitudinal edges with the usual combs

19, for co-action with the cutting edges of the blade. This guard is provided centrally with a longitudinal groove 20, adapted for snugly receiving the clamp 16. The guard 18 has a tubular handle 21, rigidly secured thereto, and this tubular handle receives the rod and its socket. The rear end of the rod is screw-threaded for receiving a clamping nut 22, having screw-threaded engagement therewith.

45 As more clearly shown in Figure 4, the guard 10 is provided with pairs of sharpening or honing elements or surfaces 23. These sharpening or honing elements or surfaces are arranged upon opposite sides of the tubular handle 21 and extend longitudinally of the guard 18, terminating 15 at the opposite ends of the same. These sharpening or honing elements or surfaces 23 may be formed of separate elements inserted within grooves 24, formed in the forward face of the guard 18, and held therein by any suitable 20 means. These sharpening or honing elements or surfaces may be formed of glass, stone, composition, or hard metal, such as hard steel. Instead of forming these honing elements or surfaces separate from the guard 18, and attaching 25 the same thereto, they may be made integral with the guard, the entire guard being formed with hard metal, such as steel.

50 With the blade clamped in the holding unit, to sharpen the blade, the entire razor is inverted and the cap 10 placed in the palm of the hand, such as the left hand. The nut 22 is now sufficiently unscrewed to permit of the upward movement of the guard 18 from the clamp 16, so that the walls of the groove 24 will clear 30 the clamp. The tubular handle 21 being grasped in the right hand, the guard 18 may be oscillated, with the honing elements or surfaces 23 in engagement with the opposite edges of the blade. This rotary or oscillating movement of 35 the guard causes the honing elements to have a diagonal stroke in engagement with the edges of the blade, which is important in properly sharpening the edges and straightening out bent 40 portions of the same. If it is desired to sharpen 45 the opposite side of the blade, the nut 22 is removed and the guard entirely separated from the rod. The socket 12 is now disconnected from the screw-threaded stud, whereby the clamp 16 may be removed. The blade is now separated from 50 the cap and inverted, and again applied to the same, and held thereon by the clamp and associated elements. The guard is again applied to the cap 10, with the nut 22 adjusted to permit 55 of the proper turning movement of the guard,

whereby the opposite surfaces of the edges of the blade may be properly sharpened. After the operation is completed, the nut 22 is screwed up and the guard clamped against the blade and cap. The safety razor is now ready for use in the usual manner. The honing or sharpening elements or surfaces in no way interfere with the normal shaving use of the safety razor, nor do they materially increase the weight or 10 size of the device. The razor may be manufactured with the honing or sharpening feature without materially increasing its cost of production.

While it is preferred to provide the blade-holding unit with the clamp 16, the invention is not necessarily restricted to the use of the same, as the clamp 16 may be omitted and the invention used with some degree of success. The blade-holding unit may consist of the cap 20 without the clamp 16.

It is to be understood that the form of my invention herewith shown and described, is to be taken as the preferred example of the same, and that various changes in the shape, size, and 25 arrangement of parts may be resorted to without departing from the spirit of the invention, or the scope of the subjoined claims.

Having fully described my invention, what I claim is:

30 1. A safety razor comprising a cap having a screw-threaded stud disposed upon the rear side of the same and permanently attached thereto, a stem provided at its forward end with a screw-threaded socket for detachably receiving the 35 stud, said socket being adapted to hold a blade

upon the rear side of the cap, the rear end of the stem being screw-threaded, a tubular handle for insertion upon the stem, a guard rigidly mounted upon the tubular handle and adapted to be arranged at the rear of the cap, a plurality of blade sharpening strips mounted upon the forward side of the guard upon opposite sides of the central axis of the guard and rigidly connected therewith throughout substantially the entire areas of the strips, and a nut having 10 screw-threaded engagement with the rear end of the stem and constituting the sole connection between the stem and the tubular handle for regulating the relative longitudinal movement between these parts. 15

2. A safety razor comprising a cap having a screw-threaded stud disposed upon the rear side of the same, a stem provided at its forward end with a screw-threaded socket for detachably receiving the stud, said socket being adapted to 20 hold the blade upon the rear side of the cap, the rear end of the stem being screw-threaded, a tubular handle directly mounted upon the stem and its socket, a guard rigidly mounted upon the forward end of the tubular handle 25 and adapted to be arranged at the rear of the cap, blade sharpening strips imbedded within the forward side of the guard and extending upon either side of the central axis of the guard, and a nut having screw-threaded engagement with 30 the rear end of the stem and adapted to engage and disengage the rear end of the tubular handle.

EDWARD HOLBROOK WYMAN.
